UNITED STATES PATENT OFFICE

MAURICE SAMBURG, OF BROOKLYN, NEW YORK, ASSIGNOR TO LOCK PATENTS HOLDING CORPORATION, OF NEW YORK, N. Y., A CORPORATION OF NEW YORK

COMBINATION LOCK

Application filed March 3, 1928. Serial No. 258,722.

My invention relates to improvements in permutation or combination locks; and the same has for its object more particularly to provide a simple, compact and reliable device which is controlled by permutation mechanism manipulated in accordance with certain combinations, and which is readily adjusted to change the combination at will.

Further, said invention has for its object to provide a device of the character specified, which comprises a very few inexpensive parts assembled for efficient and reliable operation.

Further, said invention has for its object to provide a device of the character specified, in which the permutation mechanism controlling the actuating member must be returned to registering position to release said actuating member before the device can be adjusted to change the same to a new combination.

Further, said invention has for its object to provide a device of the character specified, in which each of the tumblers thereof consists of concentric parts adapted to be locked together as a unit during manipulation thereof for effecting the locking or the releasing of said actuating member for the locking means, and in which the inner of said parts is adapted to be locked against movement as the outer thereof is adjusted to change the combination.

Further, said invention has for its object to provide a device of the character specified, in which the combination changing means thereof is rendered operative to permit of the change of combination upon the movement of the actuating member for the locking means to a predetermined position.

Further, said invention has for its object to provide a device of the character specified, in which the means for locking the tumbler parts together and the means for locking the inner part thereof against movement are both controlled by movement of said actuating member.

Further, said invention has for its object to provide a device of the character specified, in which means on said actuating member for controlling the locking thereof upon movement of the tumblers or permutation mechanism from registering position is adapted to coact with the means for rendering the combination changing means inoperative to permit of the release thereof, and relative movement of the parts for changing the combination.

Further, said invention has for its object to provide a device of the character specified, in which the adjustable parts thereof are disposed in compact relation one above the other, but out of contact with each other to permit of each thereof being manipulated without affecting the parts contiguous thereto.

Further, said invention has for its object to provide a device of the character specified, in which members are disposed intermediate the successive tumblers to permit of the actuation of all, or a part of each thereof, without affecting the contiguous tumblers.

Further, said invention has for its object to provide a device of the character specified, in which said tumbler separating members are individually retained against rotational movement, and in spaced relation to each other.

Further, said invention has for its object to provide a device of the character specified, in which said separating members are slidably received in slots provided in the outer end of an axially movable member yieldable in a certain position of said actuating member to release the parts of each tumbler to permit of relative movement thereof for changing the combination.

Further, said invention has for its object to provide a device of the character specified, in which said actuating member is limited in its movement by means serving to indicate the positions thereof for retaining the same locked and free respectively when the permutation mechanism is moved from registering position, and in which said actuating member is locked by said means against displacement when it is desired to change the combination.

Other objects will in part be obvious, and in part be pointed out hereinafter.

To the attainment of the aforesaid objects and ends, my invention consists in the novel features of construction, and in the combination, connection and arrangement of parts hereinafter more fully described and then pointed out in the claims.

In the accompanying drawings:

Fig. 1 is a plan of one form of locking device constructed according to and embodying my invention;

5 Fig. 2 is a longitudinal sectional view thereof;

Fig. 3 is a section on the line 3—3 of Fig. 2;

10 Fig. 4 is an enlarged section on the line 4—4 of Fig. 1, showing the permutation mechanism or tumblers in position to release the actuating member;

15 Fig. 5 is a similar view, showing the actuating member rotated 180° to position the parts to permit of the changing of the combination;

Fig. 6 is section on the line 6—6 of Fig. 1, showing in detail a part of a stop and locking means for the actuating member;

20 Fig. 7 is an exploded view in perspective of the parts of one of the tumblers and an intermediate spacing washer;

Fig. 8 is a perspective of the supporting member and the boss thereon on which the tumblers are mounted;

25 Fig. 9 is a perspective of the lower or base member to which said supporting member is to be locked;

Fig. 10 is an exploded view in perspective of the actuating member or spindle and the 30 locking detent thereon;

Fig. 11 is a plan with the spindle in section showing the permutation mechanism in position to lock the spindle or actuating member; and

35 Figs. 12 to 15 inclusive are views similar to Fig. 11, showing the parts in the various other positions thereof.

Referring to the drawings, the device comprises as one example a plate or support 10 pivoted at 12 to the portion 14 secured to one of the relatively movable parts of the article to which the lock is to be applied, the parts 10 and 14 forming the usual hasp. A cooperating base member or plate 16 is secured 45 to the other of the relatively movable parts of the article below the plate 10 and is provided with an oval-shaped opening 18 therein adapted to receive a detent 20 for locking the parts together as hereinafter more fully described.

50 An annular boss or bearing 22 extends from the outer side of said plate 10 and has a radial slot 24 therein loosely receiving the single locking member or dog 26. The dog 26 is slightly longer than the slot 24, and is provided with rounded longitudinal edges or cam surfaces, as indicated at 28.

55 An actuating member or spindle 30 is rotatably disposed within the annular bearing 60 22 and extends at the inner end thereof below the plate 10. The detent 20 is secured to the inner part of said spindle 30 against a sleeve 32 thereon interposed between the detent 20 and the supporting member 10.

65 When the detent 20 registers with the

opening 18, the plate 10 can be raised and lowered relative to the plate 16. When the plate 10 is lowered and the spindle 30 rotated, the detent 20 extends transversely below the opening 18 and locks the parts 10 and 16 together.

70 The spindle 30 is provided with a pair of longitudinal recesses or grooves 34 and 36 of unequal size, disposed in spaced relation thereon. The smaller groove 34 is adapted to receive the dog 26, which closely fits the same, for locking the spindle against rotation, as hereinafter more fully described, and the larger groove 36 in another position of the spindle 30 is also adapted to receive the dog 26, but to permit of the partial rotation of the spindle 30 relative thereto to control the detent 20 or other locking means.

75 The radial position of the dog 26 relative to the spindle 30 is controlled by suitable 85 permutation mechanism, such as the tumblers or members 38, 40, 42, each comprising the concentric annular parts 44 and 46. The inner parts 44 are provided with central openings 48 of uniform size, the uniformity 90 in the size of the openings 48 being insured preferably by forming the several openings by the same machine during the manufacture thereof. The inner edges of the several inner parts 44 have cam notches 50 therein 95 for receiving the dog 26. The members 38, 40 and 42 are disposed about said boss 22, which closely fits the openings 48 therein, and one above the other in exposed position to permit of the actuation of each thereof independently, and the same are preferably of successively decreasing diameter, providing a step formation having horizontally extending tread portions 52 provided with suitable indicia or calibrations 54.

100 The several members 38, 40 and 42 closely fit the boss 22 to prevent play relative thereto, so that the tumblers cannot be manipulated by unauthorized persons to unlock the device by the sense of touch or hearing without knowing the combination.

105 The inner and outer parts 44 and 46 of each tumbler are adapted to be secured together for joint rotation, and to be disengaged to permit of free movement of the outer part 46 for changing the combination. For this purpose the inner edge of the outer part 46 is provided with a plurality of notches 56 (Fig. 7) arranged uniformly about the same. The inner part 44 diametrically opposite the notch 50 is provided with a reduced portion 58 providing a U-shaped groove in which is received a bifurcated or U-shaped detent or dog 60 (Fig. 7) of slightly greater length than the width of the annular part 44 and having the outer surfaces of the arms 62 thereof substantially flush with the surfaces of said member 44. The central portion 64 of the detent 60 provides a nose adapted, when projected, to be received within any one of 115

the notches 56 of the part 46, and, when retracted, radially inwardly to disengage the notch 56 and to be received within the vertical portion of the U-shaped groove 58.

5. To permit of this inward radial movement of the detent 60, the boss 22 is provided with a second radial slot 66 disposed diametrically opposite the slot 24 and receiving the yieldable spacing member 68 of substantially the same width as the slot 66. The member 68 is retained normally in position entirely within the confines of said slot 66 by means of a spring 70 disposed in a slot formed in part in the boss 22 and in part in 10 the member 68.

Annular washers or spacing members 72 are disposed intermediate the tumblers around the boss 22, and the same are retained against rotation relative thereto. Each spacing member 72 at the inner edge thereof is provided with a notch 74 adapted to register with the notches 50 in the tumblers when the same are moved to registering position in alignment with the dog 26, and at the diametrically opposite side of said inner edge is provided with an inwardly projecting tongue 76 slidably received within the spaced slots 78 in the outer end of the yieldable member 68 and retained therein against rotation and in spaced relation to each other.

A finger piece or actuating portion 80 is attached to or formed on the outer end of the spindle 30. This member 80 preferably comprises a pair of arms 82 extending radially outwardly in close relation to and over the tumblers 38, 40 and 42 and conforming in contour with the contour thereof to provide a compact structure, without interfering with the reading of the calibrations 54 and 40 with the adjustment of said tumblers. A washer 83 may be disposed around the boss 22 between the finger piece 80 and the contiguous tumbler.

Stops 84 and 86 are disposed at substantially diametrically opposite sides of the permutation mechanism upon the plate 10. A cooperating member or pin 88 carried by one end of the finger piece 80 is adapted to engage the stops 84 and 86 to limit the movement 50 of the member 80 and the spindle 30 as the same are rotated through nearly an arc of 180°. The stop 84 is so located that, when the pin 88 engages the same as shown at Fig. 1, the groove 34 becomes aligned with the dog 26. When the pin 88 engages the stop 86, the large groove 36 becomes aligned with the dog 26.

The stop 86 is mounted upon a spring 90 (Fig. 6) which normally retains the same projected through an opening 92 in the plate 10. Cooperating with the stop or detent 86 is a pin 94 disposed on the plate 10 in spaced relation to the detent 86. The pin 86 may be depressed to permit of the reception of the 65 pin 88 between the pins 86 and 94 to hold the

actuating member or spindle 30 against movement when the tumblers are being adjusted to change the combination. In this last position the groove 34 becomes aligned with the yieldable member 68.

The arrow or other mark 96 (Fig. 1) indicates the point to which the numbers or calibrations 54 on the tumblers, constituting the combination, must be brought in order to cause the several notches 50 to register or align with the dog 26 to permit of the release of the actuating member.

In operation, when it is desired to release the spindle 30, the same being shown in locked condition at Fig. 11, the several tumblers 38, 40 and 42 are moved in accordance with a given combination to bring the notches 50 into alignment with the dog 26, the several notches 50 thereof thus registering with each other, and with the notches 74 in the spacing washers 72, as shown at Figs. 4 and 12. Assuming for example that the combination is 2-3-9 when the tumblers are moved until the members 2-3-9 thereon align with the pointer 96, as shown at Fig. 1, the notches 50 then become aligned with the dog 26. When the spindle 30 is partially rotated in a clockwise direction (Fig. 1) relative to the stop 84, the parts then assume the position shown at Fig. 13, the member 26 being forced into the notches 50 to lock the tumblers 38, 40 and 42 by the cam action of the rotatable spindle. This movement causes the detent 20 to disengage the base member 16 to permit of the separation 100 of the parts 10 and 16. When the spindle 30 is rotated in a counter-clockwise direction until the pin 88 engages the stop 84, the detent 20 again engages the base member 16 and the groove 34 aligns with the dog 26. One or more of the tumblers are then rotated to bring their notches 50 out of alignment with the dog 26, as shown at Fig. 11, which forces the dog by cam action of the notches 50 into the groove 34, the dog 26 being retained therein against retraction and again securely locking the spindle 30 against movement.

In some instances it is desirable to be able to lock and unlock the device, or to effect the engagement and disengagement of the detent 20 with and from the base member 16 without working the combination. For this purpose, the spindle 30, is rotated clockwise, looking at Fig. 13 until the pin 88 engages the stop 86. The relatively wide groove 36 will then register with the dog 26, the latter being received therein, as shown at Fig. 14, when the tumblers are rotated out of registering position. It is to be noted that the size or width of the groove 36 is such as to permit of the rotation of the spindle relative to the dog 26 to actuate the detent 20 without first requiring manipulation of the tumblers to place the same in registering po-

sition with the dog 26. This permits of the actuation of the member 30 even though the notches 50 of the tumblers do not register with the dog 26.

5. When it is desired to change the combination, the detent 86 is depressed and the pin 88 is engaged between the pins 86 and 94. When the parts are in this position, as shown at Figs. 5 and 15, the small groove 34 registers with the yieldable spacing member 68. In this position, the inner parts 44 of the tumblers are locked against movement by the dog 26, and the outer parts 46, when rotated, cause the U-shaped detents 60 and the 10 yieldable members 68, now in alignment therewith, to be moved inwardly into the small groove 34. It is to be noted, looking at Fig. 5, that when the yieldable member 68 is moved inwardly the spacing washers 72 will still be retained within the slots 78 thereof. When the desired numbers on the outer parts 46 of the tumblers are brought into alignment with the pointer or mark 96, the combination is changed accordingly, and 15 the spindle 30 thereafter will be released as often as these numbers, constituting the new combination, are brought into alignment with the pointer 96. The boss 22 normally retains the detents 60 projected when the 20 same are out of alignment with the member 68.

The non-rotatable spacing members 72 serve to permit of independent movement of each tumbler as a whole, or of the outer part 25 thereof to change the combination, without affecting the contiguous tumblers, or the outer parts thereof. The spacing members 72 are supported in the slots 78 of the inwardly yieldable member 68 independently of the 30 tumblers, so that the latter may be readily rotated with a minimum of frictional resistance and without having imposed thereon the weight of the contiguous parts. Nevertheless, the tumblers 38, 40 and 42, the washers or 35 spacing members 72, and the finger piece 80 are in close relation, and are arranged one above the other to provide a compact structure of minimum projection above the plate 10. The tumblers are also in exposed position to permit of the individual and independent manipulation thereof as a whole, or 40 in part for changing the combination.

The lock embodying my said invention is adapted for general use, such as for use on 45 luggage, including trunks, valises, brief cases, and the like, and on safe deposit boxes, lockers, etc., where compactness and reliability of operation are desirable. The device of the present invention may be used to operate 50 various types of locking mechanism.

By my invention it is permitted to lock and unlock the device, either by first manipulating the tumblers in accordance with the combination therefor to release the actuating 55 member 30 for the locking means, or without

manipulation of said tumblers, as desired. The combination may also be conveniently changed at will.

The parts of the improved lock being entirely exposed and compactly assembled 70 adapts the lock for ready attachment to any object with very little trouble and without the necessity of extensive alterations or changes.

I claim:

1. A lock comprising an actuating member, locking means controlled thereby, permutation mechanism adapted to be moved to lock and release said actuating member, and including means for changing the combination 80 thereof, locking means for rendering said combination changing means normally inoperative, and means controlled by said actuating member for releasing said locking means in a certain position of said actuating member 85 to permit of the changing of the combination.

2. A lock comprising an actuating member, locking means controlled thereby, permutation mechanism adapted to be moved to lock and release said actuating member, 90 and including means for changing the combination thereof, means for rendering said combination changing means normally inoperative, and means on said actuating member 95 cooperating with permutation mechanism to effect the locking of said actuating member, and disposed in inoperative relation to said third means when said actuating member is locked; said last named means being movable upon the release of said actuating member to a position in operative relation to said third means for releasing said combination 100 changing means.

3. A lock comprising an actuating member, locking means controlled thereby, permutation mechanism adapted to be moved to lock and release said actuating member, and including means for changing the combination thereof, means for rendering said combination changing means normally inoperative, means on said actuating member 105 adapted to cooperate with said mechanism for effecting the locking of said actuating member in one position thereof, means on said actuating member adapted to cooperate 110 with said mechanism to render the same inoperative to lock said actuating member in another position thereof; said last named means being disposed in inoperative relation to said third means when said actuating member is locked, and certain of said last 120 named means being movable upon the release of said actuating member to a position in operative relation to said third means for releasing said combination changing means.

4. A lock comprising an actuating member, locking means controlled thereby, permutation mechanism adapted to be moved to lock and release said actuating member, and including relative movable parts, means 130

for locking said parts together for joint movement, and means on said actuating member cooperating in one position thereof with said permutation mechanism to control the movement of said actuating member, and cooperating in another position of said actuating member with said second named locking means for releasing the same.

5 5. A lock comprising an actuating member, locking means controlled thereby, permutation mechanism adapted to be moved to lock and release said actuating member, and including relatively movable parts, means for locking said parts together for joint 10 movement, and means on said actuating member cooperating in one position thereof with said permutation mechanism to lock said actuating member against movement, and cooperating in another position of said 15 actuating member with said second named locking means to permit of the release thereof; said actuating means in said last named position serving to lock said parts contiguous thereto against movement.

20 6. A lock comprising an actuating member, locking means controlled thereby, permutation mechanism adapted to be actuated to lock and release said actuating member, and including parts adapted to cooperate 25 with said actuating member and parts movable relatively to said first named parts, means for locking said parts together for effecting joint movement thereof, and means controlled by said actuating member for 30 locking the contiguous cooperating parts against movement and for releasing said last named locking means, whereby to permit of relative movement of said parts to effect a 35 change in the combination.

40 7. A lock comprising an actuating member, locking means controlled thereby, permutation mechanism adapted to be moved to lock and release said actuating member, and including relatively movable parts, means for locking said parts together for joint movement, and means cooperating with said last named means in certain positions of said permutation mechanism and said actuating member for releasing said 45 second locking means, whereby to permit of relative movement of said parts to effect a 50 change of combination.

55 8. A lock comprising an actuating member, locking means controlled thereby, permutation mechanism adapted to be moved to lock and release said actuating member, and including relatively movable parts, means for locking said parts together for joint movement, means on said actuating member cooperating in one position thereof with said permutation mechanism to lock said actuating member against movement, and means on said actuating member cooperating with said permutation mechanism in another position of said actuating member to

render the former inoperative to lock said actuating member; certain of said last named means in another position of said actuating member cooperating with said second named locking means to permit of the release thereof.

70 9. A lock comprising an actuating member, locking means controlled thereby, tumbler members disposed about said actuating member, and including relatively movable concentric parts, means controlled by relative movement of said actuating member and said tumbler members for releasing and locking said actuating member, and means controlled by said relative movement for releasing and locking said parts.

75 10. A lock comprising a support, an annular bearing extending from said support and having radial slots therethrough, an actuating member rotatably disposed within said bearing and having a recess therein, locking means controlled thereby, a plurality of tumblers disposed about said annular bearing and including inner notched parts and outer parts movable relative thereto, a dog disposed in one of said slots, and adapted to be received within said recess in the locking position of said tumblers to effect the locking of said actuating member, axially movable detents for locking said tumbler parts together, and a spacing member disposed in the other of said slots; said spacing member being receivable into said recess in another position of said actuating member to permit of the release of said parts.

80 11. A lock comprising an actuating member, locking means controlled thereby, tumblers disposed one above the other about said actuating member, and each including inner and outer parts; said inner parts having reduced portions, detents disposed in said reduced portions and adapted to engage said outer parts to lock the corresponding parts together, and means controlled by said actuating member for releasing said detents.

85 12. A lock comprising a support having an annular boss thereon provided with radial slots, a spindle rotatable in said boss, tumblers disposed about said boss one above the other, and each including concentrically arranged annular parts, a member disposed in one of said slots and controlled by said tumblers to lock and release said spindle, a member disposed entirely within the confines of said second slot, and detents carried by the inner parts of said tumblers and normally retained by said boss in locking engagement with the outer of said tumblers; and a recess in said spindle adapted to align with said second slot and receive said spring controlled member to permit of the release of said outer parts of the tumblers when the detents are aligned with said second slot.

90 13. A lock comprising a support, an annular bearing extending from said support and having radial slots therein in spaced relation,

5 a spindle rotatably disposed within said bearing and having a longitudinal groove therein adapted to register with said slots, locking means controlled thereby, a plurality of disk tumblers disposed about said boss, one above the other in exposed position to permit of the manual actuation of each thereof independently, and each including an inner annular part having a notch at the inner edge thereof adapted to register with the first of said slots, and an outer annular part concentric therewith having a series of notches about the inner edge thereof, a radially movable detent carried by each of said inner parts a distance from the notch thereof equal to the distance between said slots, and adapted to engage the notches of the outer part to secure said parts together, and to align with the second of said slots when said notches of the 10 inner parts align with said first slot, a dog disposed within said first slot and received within said groove to lock said spindle and received within the notches of the inner parts to lock said inner parts and to unlock said spindle, and a spacing member disposed in the second slot and received within said groove when the same is moved into alignment therewith to permit of the inward movement of said detents to release said outer parts.

15 14. A lock comprising a support having an annular boss thereon provided with a slot, an actuating member disposed within said boss, locking means controlled thereby, a dog within said slot adapted to engage said actuating member for locking the same, a plurality of tumblers rotatably disposed about said boss one above the other in exposed relation to permit of the manual actuation of each thereof independently, and 20 having notches at the inner edges thereof adapted to register with said slot to control said dog, and a plate disposed about said boss intermediate said tumblers and retained against rotation by said boss; said plate having a notch therein in alignment with said slot.

25 15. A lock comprising a support having an annular boss thereon provided with a slot, an actuating member disposed within said boss, locking means controlled thereby, a plurality of tumblers including inner and outer relatively movable parts rotatably disposed about said boss one above the other in exposed relation to permit of the manual 30 actuation of each thereof independently, means intermediate said tumblers and said actuating member controlled by said tumblers for locking and releasing said actuating member, detents for locking said tumbler parts together for joint operation retained in locking position by said boss, and a spacing member disposed in said slot adapted to yield inwardly when said detents are aligned therewith to permit of the release of said parts.

35 16. A lock comprising a rotatable actuating member, locking means controlled thereby, permutation mechanism adapted to be moved to lock and release said actuating member, and including means for changing the combination thereof, means for rendering said combination changing means normally inoperative, and means controlled by said actuating member for releasing said last named means to permit of the changing of the combination. 70

40 17. A lock comprising a support having an annular boss thereon provided with a slot, an actuating member disposed within said boss, locking means controlled thereby, a plurality of tumblers including inner and outer relatively movable parts rotatably disposed about said boss one above the other in exposed relation to permit of the manual actuating of each thereof independently, 80 means intermediate said tumblers and said actuating member controlled by said tumblers for locking and releasing said actuating member, detents for locking said tumbler parts together for joint operation retained in locking position by said boss, a spacing member disposed in said slot adapted to yield inwardly when said detents are aligned therewith to permit of the release of said parts; said spacing member having a plurality of spaced slots therein, and plates disposed about said boss intermediate said tumblers and having tongues received within said last named slots for retaining the plates in spaced 85 relation and against rotation. 90

45 18. A lock comprising an actuating member, locking means controlled thereby, permutation mechanism for locking and releasing said actuating members in one position thereof, and including means for changing the combination thereof, means for rendering said mechanism inoperative to lock said actuating member in another position of said actuating member, and stops limiting the movement of said actuating member for indicating said positions thereof; one of said stops being movable out of the path of said actuating member to permit of the movement of said actuating member to combination changing position, and constituting a detent 100 for retaining said actuating member in said last mentioned position. 105

50 In testimony whereof, I have signed my name hereto.

MAURICE SAMBURG. 120
